UNITED STATES PATENT OFFICE.

WILLIAM K. PATRICK AND ROBERT E. L. COSTAN, OF FORT WORTH, TEXAS.

DESIGN FOR A COMIC DUCK.

41,946.

Specification for Design.

Patented Nov. 28, 1911.

Application filed July 27, 1911. Serial No. 640,950. Term of patent 3½ years.

To all whom it may concern:

Be it known that we, WILLIAM K. PATRICK and ROBERT E. L. COSTAN, citizens of the United States, residing at Fort Worth, in the county of Tarrant and State of Texas, have invented a certain new, original, and ornamental Design for a Comic Duck, of which the following is a specification, reference being had to the accompanying drawing, forming part thereof.

We claim:

The ornamental design for a comic duck, as shown.

In testimony whereof, we set our hands in the presence of two witnesses, this 14th day of July, 1911.

WILLIAM K. PATRICK.
ROBERT E. L. COSTAN.

Witnesses:

A. L. JACKSON,
J. W. STETT.
